APPARATUS FOR CLEANING AND DRESSING
BOWLING LANES

Victor Unterbrink, Ottawa, Ohio, assignee to Pines Engineering Co., Inc., Aurora, Ill., a corporation of Illinois

Filed June 26, 1962, Ser. No. 205,434

6 Claims. (Cl. 15—93)

The present invention relates to improvements in an apparatus for cleaning and applying dressing to a floor surface and is more particularly concerned with the novel construction, assembly and mode of operation of self-propelled apparatus designed to initially wipe clean and to then apply dressing to the surface of a bowling lane or other surface, and over selected areas thereof.

Bowling lanes in particular are difficult to clean and then dress because of the need to avoid the build-up of excessive quantities of lane dressing in any area or areas thereof and further because it is desirable that all lanes in a series be dressed the same so as to make them uniformly responsive to a bowling ball advanced therealong. Heretofore, bowling lanes have been swept manually and by machine sweepers and then a fine coating of lubricating oil or other dressing, liquid or viscous, has been applied to the cleaned surface as by spraying. Spraying has been found to be most unsatisfactory primarily because the spray cannot be applied evenly over the entire surface of a lane, to say nothing about a series of lanes, and further, sprayed dressing material is deposited in the gutters, in the ball-return tracks, on the foul line and even over areas of the approach surface. This latter results in the player slipping during delivery of a ball, whereas dressing deposited in the gutters and ball-return tracks accumulates on the ball surface and in the finger holes of the ball and results in finger slippage. Uneven application of lane dressing resulting in excessive accumulation of same on certain lane areas creates a sticky condition on the lane. Furthermore, an excessive build-up of dressing is gradually worn away only where the ball travels, thereby making a groove for the ball and decreasing player control.

In accordance with the present invention, means and apparatus is provided for cleaning the surface of the bowling lane in advance of the application of lane dressing which is applied in a novel manner uniformly over the entire length of the lane without material loss and without the deposit of any dressing in the gutters or on the ball return tracks. The apparatus, which is self-propelled, functions to stop short of the foul line so as to avoid any likelihood of lane dressing being deposited thereon and subsequently picked up by the shoe of a bowler who may touch the foul line or pass slightly beyond same.

These advantages are attained by the provision of a novel dressing applicator which follows closely behind means for wiping the lane clean of all foreign matter, including a previously applied lane dressing. The apparatus herein disclosed is self-propelled and it has the advantage of applying the dressing directly onto the lane surface in such manner that there is no possibility of any dressing being deposited in the gutters or on the ball return tracks. Further, the apparatus is such that application of lane dressing stops short of the foul line.

2

It is therefore, an object of the invention to provide an apparatus having the foregoing advantages.

Another object is to provide a self-propelled apparatus of the character referred to which is entirely automatic in its operation and is under complete control of the operator at all times.

Another object is to provide, in a single apparatus, novel means to remove previously applied dressing and dirt from the surface of a bowling lane and to apply a fresh layer of dressing onto the surface immediately after it has been so cleaned.

Another object is to provide a novel lane dressing applicator.

Another object is to provide a rugged, power-operated apparatus of the character described with novel structural characteristics that render it highly efficient in use, inexpensive to manufacture and use, simple to operate and one which includes novel means to prevent application of dressing to any surface not intended to receive such dressing.

The structure by means of which the above noted and other advantages and objects of the invention are attained will be described in the following specification, taken in conjunction with the accompanying drawings showing preferred illustrative embodiments of the invention, in which:

FIG. 1 is a perspective view of a lane cleaning and dressing applying apparatus embodying the features of the invention;

FIG. 2 is a top plan view of the apparatus, showing the housing and end panels removed;

FIG. 3 is an elevational view of the left-hand side of the apparatus as viewed in FIG. 2, showing a portion of a bowling lane in section;

FIG. 4 is an elevational view of the right-hand side of the apparatus as viewed in FIG. 2, showing part of the end wall broken away;

FIG. 5 is a horizontal sectional view of the applicator roller and its mounting, taken substantially on line 5—5 of FIG. 4;

FIG. 6 is a transverse sectional view of the applicator roller, taken on line 6—6 of FIG. 5; and

FIG. 7 is a view similar to FIG. 6, showing a modified form of roller construction.

Bowling lanes are constructed of wood having requisite degrees of hardness to resist wear at points of ball impact and to assist friction engagement between the lane and ball during a major distance of its travel down the lane. These respective lane areas are constructed of hard maple and soft pine. All surfaces are coated with lacquer and unless protected by a suitable lane dressing, the lacquer tends to burn from frictional impact, to build up around points of ball impact and, not infrequently, to accumulate on the ball. Obviously, the application of too much dressing anywhere along the length of the lane, or in the gutters, as usually occurs when a dressing is applied by spraying, will result in such dressing accumulating on the ball and in the finger holes thereof.

The apparatus disclosed in the accompanying drawings is designed to apply dressing uniformly on any smooth surface and particularly on the surface 11 of a bowling lane. The apparatus functions to wipe the lane surface clean prior to the application of the lane dressing thereon, the application of which is brought to a halt automatically when the apparatus approaches the foul line

indicated at 12 located adjacent the upwardly inclined ends 13 of gutters 14.

Referring now to the exemplary embodiment of the apparatus shown in FIGS. 1 to 6, and particularly to the FIG. 1 disclosure, the apparatus has the general shape of a substantially rectangular shallow body including a housing comprising a cover 15, removable end panels 16 and a handle generally indicated at 17. The housing 15-16 is of a width substantially greater than the width of the bowling lane and it encloses a basic frame structure including upstanding end plates 18, suitably connected together rigidly as by means of a perimeter frame 19 connected to the lower margins thereof. The end plates 18 each have a bracket 21 secured firmly, as by welding, to one side edge thereof to provide a mounting for handle 17 which is pivotally connected thereto as by bolts 22.

A pair of shafts 23 (FIG. 2) each carrying rollers 24, extend between end plates 18 and are journaled therein, one adjacent each side edge near the bottom edges thereof. The rollers 24 preferably are fabricated of suitable plastic material, such as "nylon," and they constitute means to support the apparatus upon the surface being dressed. As will be explained presently, one of the shafts 23 is power operated so as to be rotatably driven to drive its rollers 24 for advancing the apparatus along the lane while in use. Each end plate 18 also mounts, on its outside face, a rigid stub shaft 25 carrying a wheel 26 of a diameter to dispose its lower perimeter below the surface of the bowling lane upon which the apparatus is placed. They function, however, as wheels to support the entire apparatus above a surface over which it is wheeled when not in service and, more important, they cooperate with the normal upward inclination 13 of the gutters 14 for a purpose to be explained presently.

With particular reference to FIGS. 3 and 4, the basic frame structure and particularly end plates 18 mounts a power driven surface cleaning assembly, generally indicated at 27, and a power driven lane dressing applicator assembly, generally indicated at 28. The surface cleaning assembly 27 is a self-contained unit arranged at the forward or leading side of the apparatus (left-hand end as viewed in FIG. 4). It includes a roll 29 of suitable disposable sheet material, preferably an unwoven soft cotton cloth, that is mounted on a shaft 31 having its end journaled for free rotation one in each of a pair of mounting plates 32, one arranged on the inside face of each end plate 18. These mounting plates each carry a back plate 32a that has its side edges guided for vertical sliding beneath flanges 33 secured to or otherwise formed on said end plates. Each back plate 32a has a boss 34 (FIG. 3) on its outwardly disposed face that projects freely through a guide slot 35 opening onto the top edge of the related end plate 18. Bosses 34 constitute journals for a take-up shaft 36 bridging plates 32 and extending parallel to but spaced forwardly of shaft 31. Take-up shaft 36 projects outwardly of one end plate 15, as best shown in FIG. 3, and mounts firmly thereon a toothed wheel 37 which constitutes means for connecting said shaft with a power source operable for imparting step-by-step rotation to said take-up shaft.

Referring now to FIG. 4, the web 29a of roll 29 is carried downwardly and is trained around a cushioned roller 38, journaled at its ends in said mounting plates 32 and adjacent the lower edges thereof, and then upwardly around take-up shaft 36. A pair of springs 39 (one shown in FIG. 3) are bridged across bosses 34 so as to normally urge plates 32 and their shafts and roller downwardly to maintain web 29a in surface contact with the surface of the bowling lane or other surface being treated. Maximum downward movement of said surface cleaning assembly is limited by abutment of bosses 34 with the bottom ends of the respective slots 35. It should be apparent that the entire surface cleaning assembly may be removed from the apparatus as a unit, upon disengaging springs 39 from bosses 34 and lifting the assembly

out of the apparatus, thus facilitating replacement and threading of a new cloth around the roller and shafts thereof.

In operation, insofar as the structure has been described, the apparatus is guided manually along the bowling lane surface toward foul line 12 so as to advance the web of roll 29 across said surface for sweeping same and wiping up all foreign particles thereon, including previously applied dressings. At the same time, the web 29a is slowly advanced from the supply roll 29 to take-up shaft 36, so as to present a clean web surface to the lane surface being cleaned. The drive means to accomplish this will be described presently.

The power operated lane dressing applicator assembly 28 includes a large roller 41, best shown in FIG. 5, adapted to retain a roll of dressing impregnated webbing 42. The roller 41 is comprised of a tubular shell 43 firmly connected at one end to a large diameter hub portion 44 having an axial stud 45 extending outwardly thereof and journaled in a bearing 46 mounted in a plate 47 secured, as by welding, to the end plate 18. A rigid axial stud 48 extends into and is substantially coextensive with shell 43. The shell 43 is slit longitudinally as at 49 (FIG. 6) for a purpose to be explained presently.

A removable cover portion 50 is telescoped normally over the open end of shell 43 and has an axial stud 51 integral therewith and journaled, as at 52, in a mounting plate 53 held in place in an opening 54 in the other end plate 18 by turn-buttons 55. This assembly is such that upon release of the turn-buttons the mounting plate 53 and cover portion 50 may be removed readily so as to expose the interior of roller 41 to admit insertion of the roll of dressing impregnated webbing 42. When the webbing roll is in place, the free end of its web is drawn out through slot 49 and is extended sufficiently to be wrapped around the outside of a foam type of cushioning material 56 adhesively secured to the outside circumferential surface of shell 43.

The roller assembly is located in the apparatus in a position to permit the bottom circumferential surface of the web on shell 43 to contact the lane surface. Means is provided in the form of a chain drive comprising a sprocket 57 carried on stud 45, a chain 58 and a sprocket 59 on the shaft 61 of an electric motor 62 mounted on one end plate 18, for rotatably driving said roller during use. In this manner the dressing impregnated webbing is moved rapidly relative to the contacted surface so as to cause the dressing therein to be applied to the surface. When the exposed area of webbing is relieved or substantially relieved of its dressing, the webbing is pulled outwardly through slot 49 and the used portion may be severed therefrom by any suitable means. Applicant has found that a grooved backing bar 63 carried by plate 53 and over which the webbing may be laid, affords a surface over which a cutting knife can be drawn to sever the used portion of the web. A sufficient quantity of unused webbing is then withdrawn from the roll and the roller wrapped with same.

FIG. 7 is illustrative of a roller 41a comprised of hinged halves 41b-41c adapting the roller to be opened without removal from the apparatus for inserting therein a roll of webbing.

A motor 64 is carried by the other end plate 18 and it has its driven shaft 65 extending outwardly through said plate and mounting firmly a sprocket 66 (FIGS. 2, 4) having a drive connection through an endless chain 67 with a sprocket 68 carried firmly on the projecting end of one of the roller carrying shafts 23 for driving same. Both motors 62 and 64 are connected in a common electrical circuit having a switch 69 (FIG. 1) preferably mounted on or adjacent to the hand-grip portion 17a of handle 17 so as to be under control of the operator at all times. With such common control, the wiper is driven at all times during driving operation of rollers 24.

To drive the wiper take-up shaft 36, the end of the

applicator roller shaft 51 projects through the mounting plate 53 (FIG. 5) and mounts firmly thereon an eccentric pin 71. The pin extends through an aperture in one end of an arm 72 (FIG. 3) the other end of which is formed with a tooth 73 disposed for engagement with the teeth of wheel 37. A suitable guide strap 74 is provided for said arm 72. A spring 75 functions to urge the tooth 73 into engagement with the toothed wheel 37 at all times. During operation of motor 62, and rotation of roller 41, the arm 72 is reciprocated so as to engage successive teeth in said wheel 37. This action imparts a step-by-step rotation to take-up shaft 36 for advancing the wiping cloth over roller 38 during machine operation. Reverse rotation of take-up shaft 36 is prevented by a spring-loaded pawl 76 engaged with toothed wheel 37.

In order to control the quantity of dressing delivered by the roller 41, the operating speed of said roller is controlled through adjustment of a rheostat 77 connected in the circuit to drive motor 62 and mounted on one of the end plates 18. As best shown in FIG. 4, the rheostat includes a manually adjustable level 78 having a control line 79 leading from it to handle portion 17a.

In use, the apparatus is positioned at the pin setting end of the bowling lane with its outrigger wheels 26 overhanging gutters 14 so that it is supported on the lane surface by rollers 24. The motors 62 and 64 are started whereupon the driven rollers 24 advance the apparatus toward foul line 12 at a predetermined uniform rate of speed while the applicator roller is being rotated. During such advance, the lane dressing applicator roller 41 is rotated at speeds determined by the setting of rheostat 77 and the web is advanced onto its take-up shaft 36 during such operation.

Dressing is applied to the cleaned lane surface in the form of a uniform thin layer. When the apparatus approaches the foul line, the outrigger wheels 26 initially engage and then ride up the inclined ends 13 of the gutters 14. It should be noted that these wheels are located ahead of the rotating applicator. Consequently, when said wheels climb out of the gutters, the applicator roller is raised out of contact with the lane surface and lane wiping and all application of lane dressing is thereby stopped. As this occurs ahead of the foul line, there never is any possibility of lane dressing being deposited on or within the area closely adjacent to or beyond said foul line even though the operator may fail to stop operation.

From the foregoing description, it is believed that the nature of the invention and the manner in which it is to be carried out will be readily apparent to those skilled in the art.

What I claim and desire to secure by Letters Patent of the United States is:

1. Apparatus for cleaning and dressing a bowling lane comprising, a frame structure including spaced end plates, rollers supporting said frame structure for movement on said lane, drive means for at least some of said rollers, mounting plates removably mounted one on each end plate, an axle journalled at its ends in said mounting plates, a take up shaft journalled at its ends in said mounting plates, a roller journalled at its ends in said mounting plates, a web of fabric material carried by the axle and trained over the roller and then around the take-up shaft, spring means to urge the mounting plates downwardly to maintain the web in contact with the lane, a hollow roller journalled at its ends in said end plates and having surface contact with the lane, said hollow roller having a longitudinal slot therein, a roll of material enclosed in said hollow roller and having its web extended through said slot and wrapped around the circumferential surface of said hollow roller, and drive means for rotating said hollow roller and takeup shaft.

2. Apparatus for cleaning and dressing a bowling lane comprising, a frame structure including spaced end plates, rollers supporting said frame structure for movement on said lane, mounting plates removably mounted one on

each end plate, an axle journalled at its ends in said mounting plates, a take-up shaft journalled at its ends in said mounting plates, a roller journalled at its ends in said mounting plates, a web of fabric material carried by the axle and trained over the roller and then around the take-up shaft, spring means to urge the mounting plates downwardly to maintain the web in contact with the lane, a hollow roller journalled at its ends in said end plates and having surface contact with the lane, said hollow roller having a longitudinal slot therein, a roll of material enclosed in said hollow roller and having its web extended through said slot and wrapped around the circumferential surface of said hollow roller, and drive means for rotating said hollow roller and takeup shaft.

3. Apparatus for cleaning and dressing a bowling lane comprising, a frame structure including spaced end plates, rollers supporting said frame structure for movement on said lane, mounting plates removably mounted one on each end plate, an axle journalled at its ends in said mounting plates, a take-up shaft journalled at its ends in said mounting plates, a roller journalled at its ends in said mounting plates, a web of fabric material carried by the axle and trained over the roller and then around the take-up shaft, means operable to rotate the take-up shaft to advance the web over the roller, spring means to urge the mounting plates downwardly to maintain the web in contact with the lane, a hollow roller journalled at its ends in said end plates and having surface contact with the lane, said hollow roller having a longitudinal slot therein, a roll of material enclosed in said hollow roller and having its web extended through said slot and wrapped around the surface of said hollow roller, and drive means for rotating said hollow roller.

4. Apparatus for cleaning and dressing a bowling lane comprising, a frame structure including spaced end plates, rollers supporting said frame structure for movement on the surface of said lane, mounting plates mounted one on each end plate for vertical adjustment, an axle journalled in said mounting plates, a take-up shaft journalled in said mounting plates, a roller journalled in said mounting plates, a web of fabric material carried by the axle and trained over the roller and then around the take-up shaft, means to impart step-by-step rotation to the take-up shaft to advance the web over the roller, spring means to urge the mounting plates downwardly to maintain the web in contact with the lane, a hollow roller journalled at its ends in said end plates and having surface contact with the lane, said hollow roller having a longitudinal slot therein, a roll of material enclosed in said hollow roller and having its web extended through said slot and wrapped around the surface of said hollow roller, and drive means for rotating said hollow roller.

5. Apparatus for cleaning and dressing a bowling lane comprising, a frame structure including spaced end plates, rollers supporting said frame structure for movement on the surface of said lane, mounting plates mounted one on each end plate for vertical adjustment, an axle journalled in said mounting plates, a take-up shaft journalled in said mounting plates, a roller journalled in said mounting plates, a web of fabric material carried by the axle and trained over the roller and then around the take-up shaft, means to impart step-by-step rotation to the take-up shaft to advance the web over the roller, means to urge the mounting plates downwardly to maintain the web in contact with the lane, a hollow roller journalled at its ends in said end plates and having surface contact with the lane, said hollow roller having a longitudinal slot therein, a roll of material enclosed in said hollow roller and having its web extended through said slot and wrapped around the surface of said hollow roller, and drive means for rotating said hollow roller.

6. Apparatus for cleaning and dressing a bowling lane comprising, a frame structure, rollers supporting said frame structure for movement on the surface of said lane,

an axle journalled in said frame structure, a take-up shaft journalled in said frame structure, a roller journalled in said frame structure, a web of material carried by said axle and trained over the roller and then around the take-up shaft, means to impart step-by-step rotation to the take-up shaft to advance the web over the roller, means to maintain the web in contact with the lane, a hollow roller journalled at its ends in said frame structure and having surface contact with the lane, said hollow roller having a longitudinal slot therein, a roll of material enclosed in said hollow roller and having its web extended through said slot and wrapped around the surface of said hollow roller, and drive means for rotating said hollow roller.
